UNITED STATES PATENT OFFICE.

ELIAS H. HAIGHT, OF ROCKFORD, ILLINOIS.

NECK-YOKE.

SPECIFICATION forming part of Letters Patent No. 278,703, dated June 5, 1883.

Application filed August 5, 1882. (No model.)

To all whom it may concern:

Be it known that I, E. H. HAIGHT, a citizen of the United States, and a resident of Rockford, in the county of Winnebago and State of Illinois, have invented a new and valuable Improvement in Neck-Yokes; and I do hereby declare that the following is a full, clear, and exact description of the construction and operation of the same, reference being had to the annexed drawings, making a part of this specification, and to the letters and figures of reference marked thereon.

Figure 1 of the drawings is a front view of my neck-yoke. Fig. 2 is a vertical sectional view. Fig. 3 is a perspective view of the pivot-bar, and Fig. 4 is a perspective view of the pole-ring.

This invention has relation to neck-yokes; and it consists in the construction and novel arrangement of parts, as will be hereinafter fully described and claimed.

In the accompanying drawings, the letter *a* designates the transverse neck-bar. Through the neck-bar *a* are passed two pins, *c*, each having a head, *d*, terminating at a shoulder, *e*, and provided with an eye, *g*, which is designed to serve as a journal-bearing. These pins are arranged with a short interval between them, and are designed to receive the journal ends *h* of the transverse pivot-bar *k*, the central portion of which is of annular form, its inner wall being conical or flaring downwardly, as indicated at *l*.

m represents the pole-ring, which is made with perforations *n* in its sides for the passage of a transverse rivet or rivets designed to fasten the leather lining, when one is used, to the ring. At the top of the ring is formed a conical pivot-post, *p*, the base of which joins the ring-wall, and the apex of which is designed, when said post is in engagement with the downwardly-flaring annular bearing *l* of the pivot-bar *k*, to extend through the upper opening of said bearing, and to be headed down upon the margin of said opening, or upon a washer between said margin and the head, as indicated at *s*.

In this manner a strong and durable neck-

yoke coupling is designed to be provided, having great flexibility, without looseness in the joints. It is arranged to provide for a swinging motion forward and back, as well as for the circular pivotal movements, which constantly occur when the neck-yoke is in use. The coupling is adapted to be attached to sticks or bars of any size or form. Any looseness of parts caused by wear can be readily taken up by heading or upsetting the journal ends of the pivot-bar and the end of the ring-post. Instead of heading down the pivot-post, it can be cast with a head, and the transverse bar cast around it, the pivot-post having been previously chalked.

A neck-yoke provided with a central enlargement or boss has had the tube or pole-ring which slips on the end of the carriage-pole connected thereto by rings having perforated ears to receive the ends of a pivoted bar, in which the shaft of the pole-ring is swiveled, prior to my invention, and I do not broadly claim such a construction. A concave plate adapted to fit the under side of the wooden portion of a neck-yoke, provided with a central hole which is countersunk inside of the plate to receive a stem extending from the holdback-ring, which is headed down in said countersink to form a swivel-joint, has also been used prior to my invention.

Having described this invention, what I claim, and desire to secure by Letters Patent, is—

In a neck-yoke coupling, the eye-pieces *c*, extending downwardly from the yoke and forming bearings for the pivot-bar *k*, having a central downwardly-flaring annular bearing, *l*, between the journal ends thereof, in combination with the pole-ring *m*, having the conical pivot-post *p*, fitting into said annular bearing *l* and headed thereon, substantially as specified.

In testimony that I claim the above I have hereunto subscribed my name in the presence of two witnesses.

ELIAS H. HAIGHT.

Witnesses:

HENRY N. BAKER,
RICHARD B. VAN VALKENBURGH.
